CLAIM

The ornamental design for a decorative ergonomic machete, as shown and described.

DESCRIPTION

FIG. 1 illustrates a design for a decorative ergonomic machete in a first side view, in accordance with the present disclosure;

FIG. 2 illustrates the design in a second side view, in accordance with the present disclosure;

FIG. 3 illustrates the design from an end view in magnified scale for clarity sake, looking at an end of the design from a left side of FIG. 1, in accordance with the present disclosure;

FIG. 4 illustrates the design from a top view, in accordance with the present disclosure; and,

(Continued)

FIG. 5 illustrates the design from a bottom view, in accordance with the present disclosure.

Dotted lines shown in the accompanying drawings are intended to illustrate environmental features, not intended to be part of the claimed drawings in the figures in which they appear.
